SAFETY BUCKLE

Harry F. George, Chicago, Ill.

Application February 22, 1943, Serial No. 476,672

4 Claims. (Cl. 24—193)

This invention relates to a safety buckle, and more particularly to such buckle that will be positive in its gripping action, is easy to operate and one that may be quickly and easily released.

In buckle construction as heretofore practiced, it has been difficult to tighten the straps to a desired degree of adjustment, or produce a sufficiently positive grip for the straps, or quickly and easily release the buckle when speed in such operation as required.

By the present invention I have produced a safety buckle having the above advantages and overcoming the above difficulties.

A further object of my invention is to provide a safety buckle not only adapted for general use, but especially adapted for use in aviators' straps and belts, with positive holding characteristics, and at the same time capable of instant release should such occasion arise.

Another object is to provide a buckle having parts that may be covered up for ornamental purposes, and be easily decorated by associated parts of a belt, strap or the like, or have decorations easily added thereto.

A still further object is to produce a buckle that is sturdy in construction, economical to manufacture, and capable of being satisfactorily and efficiently made and used in either large or small size.

Another object is to provide a buckle which in use does not injure the material of the belt or strap, does not require holes in the belt or strap, and does not cause fraying or undue wear therein.

A further object is the provision of a buckle in which crimps are formed in the belt or strap, which crimps produce a positive gripping action, and which may also be quickly and effectively released.

A still further object is to provide such a construction that to release the buckle all that is necessary is to grasp the free end of the tightened belt or strap and give it a quick outward pull.

Other objects, advantages and capabilities will later more fully appear.

My invention further resides in the combination, construction and arrangement of parts illustrated in the accompanying drawings, and while I have shown therein preferred embodiments, I wish it understood that the same are susceptible of modification and change without departing from the spirit of my invention.

In the drawings:

Fig. 1 is a perspective view of a safety buckle embodying my invention, and fragmentarily

showing the belt or strap or straps in tightened position.

Fig. 2 is a perspective view of a safety buckle without the belt or strap, and showing the buckle in partially open position.

Fig. 3 is an end elevation of the buckle in partially open position.

Fig. 4 is a longitudinal vertical section through my new buckle and showing the same in closed and fastened position, only fragments of adjacent ends of the belt or strap or straps being included.

Fig. 5 is a longitudinal, horizontal section on the line 5—5 of Fig. 3 on an enlarged scale and showing a fragmentary portion of the belt or strap that is secured to the main body portion of the buckle.

Fig. 6 is a longitudinal, vertical section of a buckle with the parts in substantially the same position as in Figs. 3 and 5, and showing a portion of the belt or strap in position therein and only partially crimped.

Fig. 7 is a view partly in longitudinal vertical section and partly in side elevation, with the buckle in completely open position so that the belt or strap may be quickly removed therefrom by a straight longitudinal pull.

Fig. 8 is a view similar to Fig. 2, but showing a modified form of means for fastening the swinging arm to the main body portion.

Fig. 9 is a fragmentary, vertical, transverse section through the fastening projection and recess of the form shown in Fig. 8, but with the parts in closed position.

Fig. 10 is a perspective, sectional view, on an enlarged scale, of one of the crimping bars.

Referring in detail to the drawings, my new buckle is shown in Figs. 1 to 7 to comprise a main body portion 1 and a pair of swinging arms 2 rigidly connected together by having at their larger end two symmetrically arranged, non-circular openings 3 and 4, separated by a cross bar 5, as seen in Fig. 3, there being inserted in said non-circular openings (one in each) the correspondingly shaped ends 6 and 7 of the spaced apart bars 8 and 9, the large ends of arms 2 being respectively fastened in place on the ends of bars 8 and 9 by cap disks 10 secured tightly in place thereon by screws 11, which are screwed into threaded openings in the ends of bars 8 and 9 as seen in Fig. 5. This arrangement positions bars 2 between the side bars 12 of body portion 1 and the cap disks 10 for rotation with relation to the body portion.

This rotation is by reason of the mounting of the ends of the securely spaced apart bars 8 and 9

in the circular openings 13 in the larger ends of side bars 12 as seen in Fig. 5. The construction just described is the same at both ends of the bars 8 and 9.

In addition to the side bars 12 the body portion 1 further comprises the plate 14, integral with the side bars or not, as desired. Secured to the rear end of plate 14 by rivets or other suitable fastening means 15 are the two spaced flanges 16 and 17 of the hollow cylinder 18, the open ends of which cylinder are snugly positioned inside of the inner side faces of the large ends of side bars 12 as seen in Figs. 1, 2 and 5. It will be seen in Figs. 4, 5, 6 and 7 that the interior diameter of cylinder 18 is larger than the exterior diameter of the rigidly spaced bars 8 and 9 by an amount to receive the crimped portions of one end S of the belt or strap sufficiently freely to permit the same to be crimped therebetween when the rigidly spaced bars 8 and 9 are rotated in one direction (toward the closed position) by movement of the swingable arms 2, and to permit the crimped portion of the belt or strap to be backed up and returned to the position shown in Fig. 7 when the arms 2 are swung to open position.

It should also be pointed out that the opposite forward and rear walls of the cylinder 18 are formed with elongated slots 19 and 20 which are substantially exactly opposite each other to permit the belt or strap to pass therethrough and through the space 21 between the bars 8 and 9 when these slots and space are in registry, as shown in Fig. 7. At this time the arms 2 have been swung backwardly until the stops or shoulders 22 thereon have contacted the stationary stops 23 on the body portion, as they do when the slots 19, 20 and 21 are in registry to receive the belt or strap.

As seen in Figs. 4, 6, 7 and particularly Fig. 10 the segmental bars 8 and 9 are left their full thickness with a circular outer face 24 at their ends (also see Fig. 3) but are formed at the edge which advances during tightening movement with teeth 25 for gripping the belt to give added positiveness when the buckle is closed and the belt crimped. These teeth also positively move the crimped portion of the belt rearwardly when releasing the buckle, and prevent the crimped portion from being cramped or binding against the inner face of the cylinder 18, thus insuring quick release of the belt when moving the arms 2 to open position. Also the bars 8 and 9 as seen best in Fig. 10 are formed with an inclined depression 26 inwardly of the end and to the rear of teeth 25 to cause the teeth to operate more effectively. While only one end is shown fragmentarily in Fig. 10, it is to be understood that both ends of both bars 8 and 9 are of similar construction.

Also the portions of bars 8 and 9 contacting the belt during tightening operation, may be formed with parallel grooves 27 to provide ridges 28 (see Figs. 4, 6 and 7) to further facilitate the gripping action on the belt.

The plate 14 is formed with a laterally extending slot 29 through which passes the other end S² of the belt or strap, which is doubled back upon itself and fastened together by rivets R or other suitable fastening means as best understood in Fig. 4.

The free end of each of the swingable arms 2 is formed with a recess 30 adapted to receive the outwardly extending pin 31, formed with a head 32, when the arms are swung to closed position. In order to releasably lock the arms 2

in closed position, each of these arms has pivoted thereto just to the rear of the recess 30 by pins 33 flanges 34 of a cross bar or latch 35. Each of flanges 34 is formed with a recess 36 in such position that when the arms 2 are swung to fully closed position the recesses 36 will move over pins 31 to such position that recesses 36 will extend in a direction at right angles to recesses 30 as seen in Fig. 1. This locks the buckle in closed position until the flanges 34 are swung about the pins 33 until the toe 37 of each of these flanges is moved away to clear pins 31 by upwardly swinging latch 35 as viewed in Fig. 1. This will be effected by the operator grasping the free end X of the belt or strap S with his hand and pulling upwardly on the same as viewed in Figs. 1 and 4 which instantly releases the toes 37 from pins 31 and swings arms 2 to the position shown in Fig. 7 at which time the belt or strap is free to slide through the registering slots 19, 20 and 21 and out to release the buckle and belt from each other.

The structure just described is usable in any capacity large or small, such as for watch wrist bands, trunk straps, apparel belts, aviation, and for any other purpose for which such buckle is adapted. The belt or strap may pass entirely around the object or body to which it is applied, when used as a belt, but in some cases, as in aviation, it may consist of two straps, one of which is secured at one end to the buckle body portion 1 (as shown in Fig. 4) and at the other end to the seat, back or other support in the airplane, and the other strap being secured at one end to the seat, back or other support, and at the other end releasably fastened in the buckle as described above.

Should the person wearing such buckle in the airplane, require to be quickly released, all he has to do is to grasp the free end X of the belt or strap with his hand, pull it outwardly or upwardly away from the buckle to the position shown in Fig. 7 and he is free, because the belt or strap will then quickly slide out of the buckle. The upward pull on end X of the belt or strap, will swing the latch bar 35 and toe 37 to the position shown in Figs. 2, 3, 6 and 7 and free the toe from pin 31. As soon as the arms 2 are moved to the closed position, the operator will, with his fingers, move the latch 35 from the position shown in Fig. 3 to the position shown in Fig. 4 which locks the buckle until the latch is again moved upwardly to free toe 37 from pin 31.

In Figs. 8 and 9 are shown a modified form of means for releasably latching the arms 2' to the side bars 12'. In this form the latch plate 35 and toe 37 are dispensed with and there is formed on the inner face of the free end of each of arms 2' a protuberance 40 (preferably pressed inwardly from the outside), and there is formed on the outer face of the free ends of each of the side bars 12' a depression 41 to register with and receive the projections 40 with a snapping action when the arms 2' are closed with relation to the side arms 12'. Otherwise the structure and operation of the buckle is the same as in the first described form.

As will be understood the free end of the belt or strap, when the arms 2 stand in the position shown in Fig. 7, may readily be pushed through the registering slots 19, 20 and 21 and when the belt or strap is pulled through the buckle to the desired amount, the arms 2, or 2', will be moved to closed position and the latch pushed shut.

The belt or strap, when desired, will be released as described above.

Fig. 1 shows that when the belt or strap is in position in the buckle and the buckle closed, the buckle is largely concealed from sight and hence more ornamental than if all exposed in the front. Also a crest, stone or other ornamentation may be readily applied to the outer face of the latch plate 35.

In the present invention the belt is held in the buckle frictionally against the inner face of the cylinder 18 by a plurality of releasable crimps and this furnishes a very efficient snubbing action.

Having described my invention, I claim:

1. In a buckle, in combination, a relatively stationary body portion having a non-rotatable hollow cylindrical member formed in its sides with oppositely positioned slots, a member rotatably mounted in said body portion and having an elongated open-sided slot therein, an arm on each end of the rotatable member and fixed thereto to rotate said member, and a latch plate pivotally mounted at its ends to said arms, and a strap adapted to be freely passed through all of said slots when the slots are in lateral registry and to be crimped when the slot of the rotatable member is out of lateral registry with the slots in the hollow cylindrical member.

2. In a buckle, in combination, a relatively stationary body portion having a non-rotatable hollow cylindrical member formed in its sides with oppositely positioned slots, a member rotatably mounted in said body portion and having an elongated open-sided slot therein, an arm on each end of the rotatable member and fixed thereto to rotate said member, and a latch plate pivotally mounted at its ends to said arms, and means on said latch plate for releasably locking the arms to the body portion when the arms are moved thereagainst to crimp a strap passing through said slot and to freely release the strap when the strap is pulled laterally against the latch plate.

3. In a buckle adapted to releasably hold in

tightened position a belt, strap and the like, in combination, a relatively stationary body portion having fixed thereto a hollow cylinder having a slot in each of its oppositely positioned side walls, a tightening member rotatably mounted in said body portion and having an elongated, open-sided slot therein, said tightening member having fixed thereto at each end an arm, a latch bar pivotally mounted to each of said arms, said latch bar having means for releasably locking the arms to the body portion when the arms are moved close to the belt, strap and the like with the latch bar substantially parallel with the adjacent portion of the belt, strap and the like, and the latter crimped in the tightening member and cylinder, the buckle being instantly releasable by an outward pull upon the adjacent extending free end of the belt, strap and the like.

10 4. In a buckle adapted to releasably hold in tightened position a belt, strap and the like hereinafter referred to as a strap, a stationary portion having a non-rotatable hollow cylindrical member formed in its sides with oppositely positioned slots, a rotatable tightening member adapted to receive therethrough a strap to be crimped when tightened and uncrimped when the buckle is loose, an arm fixed to said rotatable tightening member, the strap being crimped in the cylindrical member when the arm is moved close to the stationary portion, said arm having latch means for releasably locking the arm to the stationary portion, the strap having a free end extending beyond the free end of the arm, whereby the operator may grasp the free end of the strap and by an outward pull instantly release the strap from the buckle, said latch means and stationary portion having interlocking elements that are interlocked when the strap is 20 close to the stationary portion and are disengaged by said outward pull on the end of the strap.

25 5. In a buckle adapted to releasably hold in tightened position a belt, strap and the like hereinafter referred to as a strap, a stationary portion having a non-rotatable hollow cylindrical member formed in its sides with oppositely positioned slots, a rotatable tightening member adapted to receive therethrough a strap to be crimped when tightened and uncrimped when the buckle is loose, an arm fixed to said rotatable tightening member, the strap being crimped in the cylindrical member when the arm is moved close to the stationary portion, said arm having latch means for releasably locking the arm to the stationary portion, the strap having a free end extending beyond the free end of the arm, whereby the operator may grasp the free end of the strap and by an outward pull instantly release the strap from the buckle, said latch means and stationary portion having interlocking elements that are interlocked when the strap is 30 close to the stationary portion and are disengaged by said outward pull on the end of the strap.

35 6. In a buckle adapted to releasably hold in tightened position a belt, strap and the like hereinafter referred to as a strap, a stationary portion having a non-rotatable hollow cylindrical member formed in its sides with oppositely positioned slots, a rotatable tightening member adapted to receive therethrough a strap to be crimped when tightened and uncrimped when the buckle is loose, an arm fixed to said rotatable tightening member, the strap being crimped in the cylindrical member when the arm is moved close to the stationary portion, said arm having latch means for releasably locking the arm to the stationary portion, the strap having a free end extending beyond the free end of the arm, whereby the operator may grasp the free end of the strap and by an outward pull instantly release the strap from the buckle, said latch means and stationary portion having interlocking elements that are interlocked when the strap is 40 close to the stationary portion and are disengaged by said outward pull on the end of the strap.

HARRY F. GEORGE.
